UNITED STATES PATENT OFFICE.

WILLIAM E. T. MERRILL, OF PHILADELPHIA, PENNSYLVANIA.

BELL TOY.

SPECIFICATION forming part of Letters Patent No. 364,535, dated June 7, 1887.

Application filed October 5, 1886. Serial No. 215,351. (No model.)

To all whom it may concern:

Be it known that I, WILLIAM E. T. MERRILL, of Philadelphia, in the county of Philadelphia and State of Pennsylvania, have invented 5 a new and useful Improvement in Bell Toys; and I do hereby declare that the following is a full, clear, and exact description of the same.

My invention is an improved bell toy, and is in its essential features a modified combination 10 of the elements shown in an application filed by me in the United States Patent Office on the 4th day of August, 1886. My invention relates to that class of such toys in which the parts are actuated to perform their several 15 functions by an oscillatory or circular movement of the hand, after the manner of the toy rattle.

My object is to produce an article that may be cheaply made out of wire or the like bent 20 into attractive shape.

The invention therefore consists of a handle forming a support for the bell-hammer, and a revolving frame for supporting the bell; and it also consists in the peculiar construction of 25 the bell-supporting frame, whereby it will first operate the hammer for the stroke and immediately after present the bell to be sounded when the hammer is released.

Further, the invention consists in combining 30 with the sounding mechanism a supple-jack, or similar device, in such a manner that the rotation of the frame will also serve to operate it.

In the accompanying drawings, Figure 1 35 represents a perspective view of the toy; Fig. 2, a similar view with the supple-jack attached. Fig. 3 is a detail view of the bell and its frame.

In these drawings the handle is marked A. 40 As shown, it is in suitable form to be grasped by the hand, and is composed preferably of the wire a, bent around and upwardly, so as to be secured to itself at the point 1, thus forming a loop. Above this point of attachment the 45 wire a is continued to form a straight portion, b, upon which the revoluble frame B is adapted to be supported. The wire is bent at right angles, approximately, to the portion b, at the point 2, and at the point 3 it is again bent 50 downwardly, so as to form a support for the

spring-hammer. This hammer is substantially of the form shown in the application above referred to, and needs no particular description here, further than to state that it depends a sufficient distance to be in the path 55 of the revoluble frame B. The connection of the wire a at point 1 forms a bearing upon which the frame is adapted to revolve, it being kept in position, when the toy is properly held, by its own weight. It is necessary that 60 additional force be given to the stroke of the hammer than that which would result from the revolution of the bell about the arm b and the consequent striking of the bell against the spring-hammer, and for this purpose the 65 frame is constructed as follows: It is preferably made out of one piece of wire. The portion marked c, supporting the bell, is bent around the straight extension b of the handle in such a manner as to permit free rotary 70 movement thereon. After passing around said extension it projects outwardly and to the front of the bell, forming, with the bell-supporting arm, an acute angle. It is then bent upwardly to the point 5, and then inwardly, as at 6, to connect with the extension b, being in the same vertical plane with the lower arm just described. The second connection is also adapted to allow rotation of the 75 frame. It will thus be seen that as the spring-hammer projects downwardly far enough to be struck by the arm 6, revolution of the frame in the direction of the arrow will cause said arm to push the hammer aside from its normal position, and on the further movement of the frame the hammer will be released 80 and caused to strike the blow at the same time that the bell by its revolution is brought violently against it.

I do not wish to limit myself to the precise 90 arrangement of the parts as shown, for any slight deviation therefrom would not be a departure from the fundamental principle of my invention. Thus the handle may be fashioned of wood of suitable shape, as shown in 95 Fig. 2. A supple-jack, or similar figure, may be used in connection with the revolving frame, and this idea is embodied clearly in Fig. 2. As shown, this device is suspended from the handle-extension, so as to be struck 100

by the arm 6 on the revolution of the frame, and, being suitably jointed, will describe all sorts of fantastic movements.

I claim as my invention—

1. A bell toy consisting of a handle, a bell-hammer supported therefrom, a frame adapted to revolve upon said handle, and a bell mounted on said frame in position to be struck by the hammer when the frame revolves, substantially as described.

2. A bell toy consisting of a handle, a bell-hammer supported therefrom, a revolving support for the bell, and a frame revolving with said bell, arranged in relation thereto so as to strike the hammer in advance of the bell, for the purpose described.

3. A bell toy consisting of a handle, a bell-

hammer supported therefrom by a spring-arm, a bell, and a support for said bell adapted to revolve and strike the hammer in advance of the bell, substantially as described.

4. A bell toy consisting of a handle, a bell-hammer and supple-jack supported therefrom, a revolving frame, a bell carried thereby, the said frame being arranged to operate the bell-hammer and supple-jack, substantially as described.

In testimony whereof I have signed my name to this specification in the presence of two subscribing witnesses.

WM. E. T. MERRILL.
